Primary Examiner—Louis S. Zarfas*Assistant Examiner*—Deanne Levy(74) *Attorney, Agent, or Firm*—Brooks & Kushman P.C.**CLAIM**

The ornamental design for a multi-purpose tray, as shown and described.

DESCRIPTION

FIG. 1 is a top perspective view of a first embodiment of the tray;

FIG. 2 is a top plan view of the first embodiment;

FIG. 3 is a bottom plan view of the first embodiment;

FIG. 4 is a right side elevational view of the first embodiment, the right side elevational view of the second embodiment being identical thereto;

FIG. 5 is a left side elevational view of the first embodiment, the left side elevational view of the second embodiment being identical thereto;

FIG. 6 is a front elevational view of the first embodiment;

FIG. 7 is a rear elevational view of the first embodiment;

FIG. 8 is a top perspective view of a second embodiment of the tray;

FIG. 9 is a top plan view of the second embodiment of the tray;

FIG. 10 is a bottom plan view of the second embodiment; and,

FIG. 11 is a front elevational view of the second embodiment, the rear elevational view being a mirror image thereof.
